United States Patent Office.

WILLIAM B. WADSWORTH, OF CLEVELAND, OHIO.

Design No. 3,504, dated May 18, 1869.

DESIGN FOR AN EAVES-TROUGH FASTENER

The Schedule referred to in these Letters Patent and making part of the same.

To all whom it may concern:

Be it known that I, WILLIAM B. WADSWORTH, of Cleveland, in Cuyahoga county, and State of Ohio, have originated and designed a new Pattern for Gutter-Fasteners, of which the following is a full and clear description, reference being had to the accompanying drawings, making a part of this specification.

The drawings show two views of a gutter-fastener, of cast malleable iron, the pattern or design being cut away or curved out between the holes and bearings.

I do not claim the mechanical device herein shown; but

What I claim as my invention, and desire to secure by Letters Patent, is—

The design or pattern for gutter-fasteners, being cut away or curved out between the holes and bearings, substantially as shown and described.

Witnesses: WILLIAM B. WADSWORTH,
GEO. W. TIBBITS,
GEO. HESTER.
